DESIGN FOR A SHOE HEEL OR SIMILAR ARTICLE

Leo Sholtz, New York, N. Y.

Application May 22, 1939, Serial No. 85,123

Term of patent 3½ years

To all whom it may concern:

Be it known that I, Leo Sholtz, a citizen of the United States, residing in New York city, in the county of New York and State of New York, have invented a new, original, and ornamental Design for a Shoe Heel or Similar Article, of which the following is a specification, reference being had to the accompanying drawing, forming part thereof.

I claim:

The ornamental design for a shoe heel or similar article, substantially as shown.

LEO SHOLTZ.
